J. D. HILLIARD

ELECTRIC SWITCH

Filed Nov. 20, 1922

Inventor:
John D. Hilliard,
by Almondo S. Fenton
His Attorney.

UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

ELECTRIC SWITCH.

Application filed November 20, 1922. Serial No. 601,955.

My invention relates to electric switches of the type wherein contacts are separated beneath an arc extinguishing liquid, and more particularly to an improved arrangement of the contacts of such switches whereby the circuit may be safely and effectively interrupted.

In the operation of switches having their contacts immersed in a liquid, there is frequently produced in the switch tank high pressure due to the intense local heating and consequent dissociation and volatilization of the liquid by the arc between the contacts. This pressure may be so severe as to rupture the switch tank, and, in any case, there is grave danger of fire and explosions if the highly heated vapors and gases have easy access to the air.

It is, therefore, a principal object of my invention, to provide an arrangement of switch contacts designed to keep the arc near the bottom of the tank where it is subjected to hydrostatic pressure which assists in extinguishing it, and from whence the hot gases and vapors must pass through a considerable body of cooling liquid before they rise to the surface thereof.

Other objects and advantages will become apparent as my invention is considered in connection with the accompanying drawing, the single figure of which shows a tank 10 provided with an insulating lining 11 adapted to contain an insulating or arc extinguishing fluid 12. Annular expansion chamber casings 13 are disposed around the inner sides of the insulating lining 11 and held in place by the supports 14 which rest against the insulating lining 11. A cover 15 for the tank 10 is provided with a vent 15' to permit escape of gases from the tank and with apertures to receive insulating bushings 16 for stationary electrodes 17 of the switch, the bushings being held in place by clamping rings 18. An aperture is also provided in the tank cover 15 to allow the passage of an operating rod 20 through the stuffing box 21. An insulating primary contact chamber casing 25 is suspended from the cover 15 by the bolts 26, the heads of which are covered by insulating nuts 27, proper alignment being maintained by the spacers 28. The primary contact chamber is vented by the apertures 29 in the top member of the casing 25, and is so formed as to direct any gases generated beneath it

upwardly along its outer surface. Expansion chamber casings 32 are attached to the side members of the casing 25. The lower central portion of the casing 25 is adapted to form an arc deflecting baffle 33.

Primary contact brushes 35 are attached to the stationary electrodes 17 and engage, in the closed position of the switch, with a main bridging member 36 which is attached to the operating rod 20. Secondary contact levers 40 are pivoted at 41 to clevises 42 which are attached to the casing 25. Each secondary contact lever 40 is operated by the contact rod 20 through the insulating toggle links 43 and the pins 44 and 45.

Electrical connection between the secondary contact levers 40 and the stationary contacts 17 is maintained by the flexible strips 46. Apertures 47 in the casing 25 are adapted to allow passage of the secondary contact levers 40 to the exterior of the casing 25. The lower ends of the secondary contact levers 40 consists of cylindrical casings 60 adapted to hold the movable secondary contacts 50 which are designed to be actuated toward the center of the tank by the springs 51 which act upon shoulders 61 formed on the contacts. The nuts 52 limit the travel of the secondary contacts 50 in the direction toward the center of the tank. Good electrical connection between the secondary contacts 50 and the secondary contact levers 40 is maintained by the flexible strips 53.

In operating the switch from closed position, the rod 20 is moved downwardly to separate the bridging member 36 from the primary contact brushes 35, and to break the toggle connection between the secondary contact levers 40 which are in an inclined position and tend to drop under the force of their own weight and by magnetic repulsion, thereby facilitating the opening operation of the switch. This arrangement of secondary contact levers has the further advantage that it helps to intensify the magnetic field of the switch in the neighborhood of the secondary contacts where the final break in the circuit is made and thus increases the disrupting force which this field exerts upon any arc formed between these contacts upon their separation. Further movement of the rod 20 will cause the secondary contact members to separate, and, if the switch is loaded, an arc will be pro-

duced between these contacts. The secondary contacts and their associated conducting leads are arranged so that the magnetic field of the switch acts to force the arc 5 downwardly against its natural tendency to rise, thereby rupturing it near the bottom of the tank and insuring intimate contact between the cooling liquid and the resulting hot gases which ultimately escape to the atmosphere through the top of the tank.

The baffle 33 forms a part of the bottom of the primary contact chamber, and is provided for the purpose of protecting this chamber against the arc formed by breaking 15 the circuit.

The compression chambers 13 and 32 are filled with a compressible gas which effectively absorbs the excess pressure generated within the tank by the arc incident to separation 20 of the secondary contacts under load. The location of the chambers 13 in proximity to the point at which the circuit is finally broken is of especial advantage in that it avoids the necessity of accelerating a large 25 body of oil and this serves to prevent the generation of the excessive pressure which would otherwise be produced within the tank. The chambers 32, which are interposed directly in the path which the gases 30 generated within the tank must follow in escaping to the surface of the liquid, serve to further absorb the internal pressure which would otherwise be exerted to accelerate the liquid. The use of compression chambers to 35 absorb the pressure created in a switch tank upon the separation of the contacts under load is disclosed and claimed in my Patent 1,537,352, May, 12, 1925, which is assigned to the assignee of the present application.

40 My invention may be embodied in other forms than that shown and described, and I, therefore, do not wish to be restricted to the specific construction shown, but intend to cover by the appended claims all changes and 45 modifications within the spirit and scope of my invention.

What I claim as new and desire to secure by Letters Patent of the United States, is:—

50 1. A fluid break switching apparatus comprising a tank, means forming a chamber within said tank, primary contacts separable within said chamber, secondary contacts separable beneath said chamber within said tank, and cushioning means within said tank adjacent said secondary contacts, the arrangement being such that pressure produced by an arc between said secondary contacts is absorbed by said cushioning means.

55 2. A fluid break switching apparatus comprising a tank, means forming a chamber

within said tank, primary contacts separable within said chamber, secondary contacts separable beneath said chamber, and cushioning means in contact with the exterior surface of said chamber, the arrangement being such that pressure produced by an arc between said secondary contacts is absorbed by said cushioning means.

60 3. A fluid break switching apparatus comprising a tank, means forming a chamber within said tank, primary contacts separable within said chamber, secondary contacts separable beneath said chamber, and cushioning means in contact with the inner surface of said tank and the outer surface 70 of said chamber, the arrangement being such that pressure produced by an arc between said secondary contacts is absorbed by said cushioning means.

65 4. In a fluid break switching apparatus, a tank containing a liquid, means forming a chamber within said tank, primary contacts separable within said chamber, and secondary contacts separable within said tank beneath said chamber whereby any arc formed 80 upon their separation will vaporize liquid within said tank, said chamber being formed to direct said vapor upwardly along its outer surface.

70 5. In a fluid break switching apparatus, a tank containing a liquid, means forming a chamber within said tank, primary contacts separable within said chamber, secondary contacts separable within said tank beneath said chamber whereby any arc formed upon 85 their separation will vaporize liquid within said tank, said chamber being formed to direct said vapor upwardly along its outer surface, and cushioning means interposed in the path of said vapor, the arrangement being such that pressure produced by an arc between said secondary contacts is absorbed by said cushioning means.

75 6. An electric switch of the type wherein a circuit is made and broken within a tank 100 well below the surface of an arc extinguishing liquid comprising contacts separable in a substantially horizontal direction and connected to the switch terminals by means of conducting members, and cushioning means 105 within said tank adjacent said contacts, the arrangement being such that any arc formed by the separation of said contacts is blown downwardly by the magnetic field of the switch and pressure created thereby is 110 absorbed by said cushioning means.

80 In witness whereof, I have hereunto set my hand this 17th day of November, 1922.

JOHN D. HILLIARD.
